(57) **CLAIM**

I claim the ornamental design for an animal feces marker, as shown and described.

DESCRIPTION

FIG. 1 is an enlarged front perspective view of the novel animal feces marker;

FIG. 2 is an enlarged bottom perspective view thereof;

FIG. 3 is a top plan view thereof;

FIG. 4 is a left side elevation view thereof, the right side elevation view is identical;

FIG. 5 is a front elevation view thereof, the rear elevation view is identical; and,

FIG. 6 is a bottom plan view thereof.
